Watson E. Coleman

ATTORNEY.

UNITED STATES PATENT OFFICE.

ISAAC W. CHERRY, OF PENSACOLA, FLORIDA.

WINDOW SCREEN.

1,422,539.

Specification of Letters Patent. Patented July 11, 1922.

Application filed September 7, 1920. Serial No. 408,654.

To all whom it may concern:

Be it known that ISAAC W. CHERRY, a citizen of the United States, residing at Pensacola, in the county of Escambia and State of Florida, has invented certain new and useful Improvements in Window Screens, of which the following is a specification, reference being had to the accompanying drawings.

10 This invention relates to window screens and has for its object to provide a screen which may be raised similar to a window sash and maintained in its raised position indefinitely without the use of props.

15 Another object is to provide a screen of this character wherein the frame is composed of two frame members adapted to coincide with each other, the sides of said members being wider than the upper and lower portions, a portion of said sides being extended in angular relation thereto and formed into a tongue for sliding movement between guides carried by the window frame.

20 With the above and other objects in view, the invention consists in the improved construction and arrangement of parts to be hereinafter more particularly described, fully claimed and illustrated in the accompanying drawings, in which:—

25 Figure 1 is a vertical elevation of a window sash showing the screen applied,

Figure 2 is a fragmentary vertical elevation and sectional view of a window sash and screen, and

30 Figure 3 is a transverse sectional view of the window sash and screen.

Referring to the drawings, A designates a window frame, and B the window shutters carried by the frame, said shutters having 35 adjustable slats C adjusted by means of the rods D. The above mentioned structure forms no part of the invention.

In order to provide a screen adapted for use with the window frame using this type 40 of shutter, I provide a novel frame structure consisting of two frame members 5 and 6, said members are in vertical alignment with each other. Each member includes an upper rail 7, a lower rail 8 and an intermediate rail 9, the rail 9 may be formed integral with the frame member or attached 45 separately. The side rails 10 of the frame member are relatively wider than the upper, lower and intermediate rails, the outer portion 50 of said side rails being extended in right

angular relation to said rails to provide a flange 11, the intermediate portion of said flange being formed with a longitudinally extending crimp to provide a tongue 12, said tongue being disposed in spaced relation to 60 the main portion of the side rails and the edge thereof so as to form two shoulders 13 and 14, the purpose of which will be herein-after described.

Each of the rails 7, 8 and 9 are formed 65 with a plurality of concavo convex depressions 15 in spaced relation to each other laterally of the frame member, the depressions in each rail registering with the depressions in the adjacent rail. A sheet of 70 wire fabric 16 is disposed between the frame members 6 and 7 and is extended over the convex surface of the depressions 15 into the frame members 5 and into the concave portion of the depressions in the frame member 6. In this way the depressions of the frame members 5 and 6 serve as clamps and at the same time cause the screen fabric to form a channel 17 vertically of the screen frame, said channels being disposed in spaced 75 parallel relation to each other. These channels and depressions are formed to suit the construction of the adjusting rods D and are intended to receive the same when the shutters are closed. The wire fabric 16 is 80 secured between the frame members 5 and 6 by suitable fastening means 18 such as rivets which also serve to connect the frame members to each other and provide a substantial structure.

90 To permit the screen to be raised and lowered with ease and rapidity, I provide a pair of guide members 19, each of said members being substantially U-shaped in cross section and adapted to be secured to 95 the stiles of the window frame. These guide members are intended to receive the tongue 12 of the screen frame, the edges 20 of said guides being disposed closely adjacent the shoulders 13 and 14. In this way, the crimp 100 or tongue guides the frame in its sliding movement while the edges 20 maintain the screen in the proper position and limit lateral movement thereof so that danger of the screen being canted or jammed is eliminated.

An expandable and retractable member 21 is secured at its end 22 to the upper portion of the window frame A. This member extends over one of the rollers 23 pivot- 110

ally mounted in the upper corners of the frame. One of these members is provided for each side of the frame, and is intended to extend over the adjacent roller 23, 5 through the guide member 19 and is secured at its end 24 to the top portion of the side member 10. By this means the expandable and retractable member serves the purpose of a sash weight to permit the screen to be 10 readily raised. It is impossible for the member 21 to become entangled with the other parts of the frame as it is fully protected by the guide 19. The lower rail 8 of each of the frame members 5 and 6 is 15 provided with an extension 25 in which is mounted a latch 26 having a head on one end thereof, a retractable spring surrounding the latch, one end of said spring being secured to the head and the opposite end 20 to the extension 25, said spring being adapted to normally urge the latch member outwardly and into an opening 27 formed in the lower portion of the window frame to 25 lock the screen in place. The rail 8 of the members 5 and 6 has its intermediate portion extended inwardly to provide an opening 28 through which the fastening means E of the shutters may be passed to lock the shutters.

30 From the foregoing it will be readily seen that this invention provides a novel form

of window screen structure which permits the screen to be raised and lowered similar to a sash and maintained in its raised position without the use of props. In addition to this, the adjusting rods D of the shutters may be conveniently disposed within the channel 17 to permit the blinds to be closed without removing the screen. Another important feature is that the frame 35 is composed of two members which not only renders the structure substantial but provides means whereby the wire fabric may be firmly secured between said members. In addition to this the channel members 17 40 and the depressions 15 serve as braces to prevent bulging of the screen fabric.

What is claimed is:—

The combination with a window frame, 50 guides carried by the stiles of the window frame, of a window screen comprising a frame having side flanges, the longitudinal intermediate portion of said flanges being substantially crimped to provide a tongue, said tongue being slidable in the guides, and 55 means carried by the free edges of said flanges for holding the screen in various positions.

In testimony whereof I hereunto affix my signature.

ISAAC W. CHERRY.
